WEEPING DOLL

David Cohn, New York, N. Y., assignor to Model Plastic Corp., White Plains, N. Y., a corporation of New York

Application December 23, 1955, Serial No. 555,020

5 Claims. (Cl. 46—135)

This invention relates to weeping doll.

One object of this invention is to improve the construction disclosed in my co-pending application Serial No. 549,701, filed November 29, 1955.

Weeping dolls have been known heretofore wherein the head was formed with a pair of openings on opposite sides of the nose and spaced inwardly from the eye sockets, and means was provided to feed water through tubes to these openings so that water would come out on opposite sides of the bridge of the nose, to simulate weeping. In such construction, the water did not come out of the eye sockets or openings in the front face of the head in which the doll's eyes were mounted.

It is therefore an object of this invention to provide a doll construction in which water is fed to the eye sockets or eye openings so that the water thus fed will come out of such sockets or eye openings onto the doll's face.

With such construction, a more natural weeping appearance is simulated since the water, simulating tears, seems to come out between the eyeballs and the eye-lids of the doll's head.

It is another object of the present invention to provide a weeping doll having a head of collapsible rubber-like material, provided with integral eye sockets within each of which is mounted a doll's eye, and means to feed water to each of the sockets so that the water will come out of the front openings of the eye sockets to simulate weeping.

Still another object of this invention is to provide in a doll construction of the character described, means to feed water directly to the insides of each of the doll's eyes so that the water comes out between the eye shell and eyeball of the doll's eyes.

Yet a further object of this invention is to provide a strong, rugged and durable doll of the character described, which shall be easy to manipulate and which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the appended claims.

In the accompanying drawings in which is shown various illustrative embodiments of this invention,

Fig. 1 is a vertical cross-sectional view of a doll embodying the invention;

Fig. 2 is an enlarged cross-sectional view taken on line 2—2 of Fig. 1;

Fig. 3 is a cross-sectional view taken on line 3—3 of Fig. 1;

Fig. 4 is a cross-sectional view taken on line 4—4 of Fig. 3;

Fig. 5 is a horizontal cross-sectional view through the eye of a doll embodying the invention and illustrating a modification thereof;

Fig. 6 is a cross-sectional view taken on line 6—6 of Fig. 5;

2

Fig. 7 is a view similar to Fig. 5 and illustrating a further modification; and

Fig. 8 is a view similar to Fig. 7 and illustrating yet another modification.

5 Referring now in detail to the drawing, 10 designates a doll embodying the invention. The doll 10 comprises a doll body 11 provided with legs 13 and arms 14, all of which are made of rubber-like collapsible, soft, resilient material, which can be compressed for collapsing and 10 which will spring back to its natural shape when pressure is released.

The body 11 has usual leg holes 13a to receive pivotal portions 13b of the legs 13, and usual arm holes 14a to receive pivotal portions 14b of the arms 14. The body 15 11 has a front wall 15, a rear wall 16, side walls 17, a bottom wall 18, shoulder portions 19, and a neck portion 20 formed at its upper end with an outwardly extending flange 21.

The doll 10 may further comprise a doll's head 25 likewise made of rubber-like, soft, compressible, resilient material which may be compressed or expanded, and which will spring back to its normal shape when released. The head 25 is formed at the bottom with a neck opening 26, through which the neck 20 passes. The flange 21 contacts 25 the inner surface of the bottom of the head adjacent the neck opening 26, as shown in Fig. 1 of the drawing. The head has a top portion 27, side portions 28, and a front face 29. The front face 29 is formed with a nose portion 30, a mouth portion 31, and a chin portion 32a. On opposite sides of the bridge of the nose there is integrally formed with the front face of the head, a pair of similar sockets 32. These sockets are spaced from one another, and each is formed at the front thereof with an eye opening 33.

35 The eye openings 33 are of smaller cross-section than the largest cross-section of the cavity formed by the socket 32. Within each socket 32 is a doll's eye 35. The doll's head must be stretched to enlarge the eye openings 33 for forcing the doll's eye 35 into the socket 32. The doll's eye 35 may be of usual construction and comprises generally a front eye shell portion 36 made of hard synthetic plastic material and formed with an eye opening 37 which conforms substantially to the eye opening 33. Fitted on to the rear end of the shell 36 is a metal cap 37. The cap 40 37 has a back wall 38, from which extends forwardly and outwardly a tapered wall 39. Extending from the wall 39 is a substantially cylindrical flange 40 which is received over the outer side of the rear end of the shell 36. Within the shell 36 is an annular ring member 42 having 45 a flange portion 43 fitted within the rear end of the shell 36. The ring 43 is formed at the rear end thereof with an outwardly tapered portion 44 contacting the tapered portion 39 of the cap 37.

Pivoted within the shell 36 about a pair of horizontal 55 pins 48 is an eyeball member 49 disposed within the shell 36. It will be noted that the front of the shell is rounded to loosely receive the eyeball 49. The doll's eyes such as described, are well known and while one such doll's eye has been described, other types of dolls' eyes may be 60 employed.

Means is provided to feed water to the insides of the sockets 32 so that the water may come out of the eye openings 33 at the front ends of the sockets. To this end, the mouth 31 of the doll is formed at the inside of the head with a recess 50 communicating through a small opening 51, with the mouth opening 31. Fitted within the recess 50 is a horizontal rigid tube 53 projecting horizontally and rearwardly into the head.

Attached to the rear end of the tube 53 is a manifold 70 55. The manifold 55 may be made of hard synthetic plastic material and comprises a chamber 56 having a cylindrical wall 57 and end walls 58.

Extending forwardly from the cylindrical wall 57 is a horizontal nipple 59 received within the rear end of the tube 53 and cemented or otherwise adhered thereto. Extending downwardly from the cylindrical wall 57 is a nipple 60. Attached to the nipple 60 is the upper end of a vertical tube 61. The tube 61 projects downwardly through the neck 20 of the doll's head. Its lower end is beveled as at 63.

Mounted on an intermediate portion of the tube 61 is a syringe container 65. The syringe container 65 is likewise made of rubber-like, compressible, resilient material. The container 65 has a bottom wall 66 from which extends upwardly a cylindrical wall 67. The container 65 has a top wall 68 formed with a central, upwardly extending sleeve 69. The tube 61 passes through a sleeve 69 and is cemented or otherwise adhered and sealed thereto. The lower end of the tube 61 substantially contacts the bottom wall 66 and is beveled. The top wall 68 is formed with a vent nipple 70.

Extending outwardly from the end walls 58 of the manifold 55 are nipples 75. Received within the nipples 75 are the inner ends of flexible tubes 76. Each of the sockets 32 is formed at the rear thereof with a central through opening 80. Extending through each opening 80 is an eyelet 81 which is riveted or otherwise fixed to the rear wall 38 of the cap 37. The wall 38 is formed with a through opening 38a through which the eyelet 81 passes. The outer ends of the tubes 76 are received within the rear ends of the eyelets 81 and are cemented and sealed thereto.

The method of operation of the doll will now be described. The nipple of a bottle may be inserted into the mouth opening 31 and water will pass through the tube 53, through the chamber 56, through tube 61, into the container 65. Air is vented from the container through the vent 70. Water may be sucked into the container 65 by compressing the body 11 and the container 65 through the body and then releasing pressure. Such action will first cause air to be squeezed out of the container 65, and when the container springs back to normal shape, the reduced pressure therein will cause water to be sucked in from the bottle to the container.

After the container is full, the bottle is removed and a pacifier is placed in the mouth opening 31 to close said opening. Thereafter, the body 11 may be squeezed in such a manner as to cause collapse of the container 65. Such action will cause water to pass upwardly through the tube 61 and through the chamber 56 and through the tubes 76 to the eyelets 81. The water will drop and pass between the bottoms of the shells 36 and the eyeballs 49, and will pass out through the front openings 33 and 37 thereby simulating weeping. It will be observed that when the body 11 and container 65 are compressed, some water will be pressed out through the vent opening 70, and drop to the bottom of the body, and will pass through a small opening 98 to simulate wetting.

In Figs. 5 and 6 there is shown a modified construction embodying the invention. In Fig. 5, numeral 25a designates a doll's head provided with eye sockets 32a similar to the head 25 with its sockets 32, except that the sockets 32a do not have the openings 80 and with the further provision that sockets 32a are each formed at their inner sides with an extension 95 integrally formed with the socket. The extension 95 is provided with a rear wall 96 formed with a through opening 97. The doll's eye 35a, received in each socket is similar to the doll's eye 35, except that its cap is provided with a sleeve 98 welded or otherwise attached to the inner side thereof and received within the projection 95 of the socket 32a. The tubes 76 pass through the openings 97 and through the sleeves 98. Thus, water passing through the tubes 76 will also come out of the openings 33, that is between doll's eyes 35a and the wall of the doll's head surrounding the eye openings 33, to simulate weeping.

In Fig. 7 there is illustrated a construction similar to

Fig. 5 except that the sleeve 98 is omitted, and instead, a sleeve is formed with the eye shell 36a, similar to the eye shell 36 of Fig. 4. The tubes 76 pass through openings 97 in the extension 95 and through the sleeve 100, so that water may pass through the eye openings.

In Fig. 8 there is still another modified construction, which combines the construction of Figs. 5 and 7. In Fig. 8 the cap is provided with the sleeve 98 and the eye shell is formed with a sleeve 100 aligned with the sleeve 98.

10 The tubes 76 pass through the openings 97 in the rear wall 96 and through the aligned sleeves 98 and 100. The tubes 76 are of course, cemented in place within the sleeves 98 and 100.

It will thus be seen that in each form of the invention, 15 the water is directed not to openings spaced from the eye sockets, but into the eye sockets and passes through the eye openings to more accurately simulate tearing or weeping.

It will thus be seen that there is provided a device in 20 which the several objects of this invention are achieved, and which is well adapted to meet the conditions of practical use.

As various possible embodiments might be made in the above invention, and as various changes might be made in the embodiment above set forth, it is to be understood 25 that all matter herein set forth or shown in the accompanying drawings, is to be interpreted as illustrative and not in a limiting sense.

Having thus described my invention, I claim as new and 30 desire to secure by Letters Patent:

1. A weeping doll comprising a doll's body of resilient rubber-like material, a head on the doll's body likewise made of resilient, collapsible material, said head being formed with a pair of integral spaced eye sockets, doll's eyes within said sockets, said sockets having eye openings 35 at the front of the head exposing the front portions of the doll's eyes, said head being formed with a mouth opening, a manifold within said head, a tube connecting said mouth opening with said manifold, a tube extending downwardly from said manifold, a container of resilient collapsible material supported on said downwardly extending tube, with the lower end of the tube projecting into the container, said sockets being formed with openings within the head, and tubes connecting said manifold with the last mentioned openings in said sockets.

2. The combination of claim 1, said doll's eyes having means to anchor said pair of tubes thereto within said sockets.

3. A doll comprising a doll's head made of rubber-like material and formed with a pair of integral eye sockets having eye openings, doll's eyes in said socket partially exposed through said eye openings, each of said doll's eyes comprising a shell portion formed with an offset sleeve and a cap for said shell formed with an offset sleeve 50 aligned with the first offset sleeve, each socket being formed with an opening, tubes passing through the openings in the eye sockets and through said aligned sleeves, and means to feed water to said tubes whereby said water will pass out through the eye openings.

4. A doll comprising a head made of soft plastic material and having a face with eye sockets therein of integral construction with the face, each of the eye sockets having a front opening for exposing to view an eye within the socket, and each of the openings having an edge which simulates a lower eye lid of the eye, each socket inward 55 from said opening increasing in cross section to provide a cavity of the general shape of an eye, eyes located in the sockets and in predetermined assembled relation to the doll head, each of the eyes being an individual unit independent of the other eye and of the doll head, and each of the eyes being of a size that can be snapped into the eye socket through said front opening and of a size that is gripped by inside surfaces of the socket with a resilient pressure of the soft plastic material, a tear reservoir within the doll, conduits between the tear reservoir 60 and locations in the eye sockets where there is clearance

between the eyes and inside surfaces of said sockets, said locations being back from the openings that expose the eyes, and a passage structure leading from each of said locations to another more forward location near part of the lower eye lid edge of the socket of each eye but within the socket, the eye lid edge of the socket being closely adjacent to the eye and in such relation that water from said forward location flows between the eye and said eye lid edge of the socket to simulate tears welling up within the eyes.

5. A doll comprising a head made of soft plastic material and having a face with eye sockets therein of integral construction with the face, each of the eye sockets having a front eye opening for exposing to view an eye within the socket, and each of the openings having edges simulating upper and lower eye lids of the eye, each socket inward from said opening increasing in cross-section to provide a cavity of the general shape of an eye, eyes located in the sockets and in predetermined assembled relation to the doll head, each of the eyes being an individual unit independent of the other eye, and each of the eyes being of a size that can be inserted into the eye sockets through said front eye openings upon

expanding said openings and of a size that is gripped by the inside surfaces of the socket with a resilient pressure of the soft plastic material, a water reservoir within the doll, conduits between the water reservoir and the eye sockets to carry water into the sockets at locations back from the openings that expose the eyes, and passage means within each socket through which water received within the sockets from said conduits may pass forwardly from said locations and through the eye openings to simulate tears welling up within the eyes.
